AUTOMATIC RECORDS RETRIEVAL UNIT

John L. Gianfagna, Staten Island, N.Y., assignor to Sperry
Rand Corporation, New York, N.Y., a corporation of
Delaware

Filed Dec. 29, 1967, Ser. No. 9,986

Term of patent 14 years

Int. Cl. D14—02

U.S. Cl. D26—5

FIG. 2.

FIG. 1.

FIG. 3.

FIG. 4.

FIG. 1 is a front perspective view of an automatic records retrieval unit showing my new design;

FIG. 2 is a front elevational view thereof, the rear being essentially plain and unornamented;

FIG. 3 is a top plan view thereof; and

FIG. 4 is an elevational view taken from the side opposite that shown in FIG. 1 thereof.

The broken line representation of record cards in the views is for the purpose of illustration only.

I claim:

The ornamental design for an automatic records retrieval unit, substantially as shown and described.
